ABSTRACT

A sealing system for a covered tank, particularly a fixed gas-sealing tank in a wastewater treatment system, includes a thrust ring positioned just inside the tank rim, secured to a series of radial beams for the cover. Preferably supported on corbels anchored to the interior tank wall, the thrust ring has an outwardly extending generally horizontal flange that overlies the edge of the tank rim. To this flange and to the top of the tank rim is secured a flexible membrane seal, around the periphery of the tank. The membrane seal is easily installed, reliable as a seal, and can be efficiently replaced when needed.

FIG. 1
PRIOR ART

FIG. 2
PRIOR ART

FIG. 3
PRIOR ART

FIG. 4

4. The rim seal of claim 3, wherein the thrust ring has a top plate including said flange extending radially outwardly.
5. The rim seal of claim 3, wherein the thrust ring comprises a structural steel beam.
6. The rim seal of claim 5, wherein the thrust ring 5 comprises a box beam.
7. The rim seal of claim 1, wherein the thrust ring is positioned inward of the concrete tank rim.
8. The rim seal of claim 1, including a series of support corbels secured to an interior side of the concrete tank rim, 10 secured into the concrete, the corbels providing an upper corbel surface on which the thrust ring is supported.
9. The rim seal of claim 8, including said support corbels at 3° increments around the tank.
10. The rim seal of claim 8, including a said support 15 corbel at each radial beam around the tank.
11. The rim seal of claim 8, wherein the corbels are secured with anchor bolts to said interior side of the concrete tank rim.
12. The rim seal of claim 8, wherein the thrust ring is 20 secured to the corbels by bolts but allowing for thermal expansion movement of the thrust ring on the upper corbel surfaces, and with a slide plate positioned between the thrust ring and each corbel upper surface.
13. The rim seal of claim 1, wherein each radial beam has 25 an erection tab near the radially outer end of the radial beam, and the erection tab being secured by bolting to a mating erection tab extending from the thrust ring.
14. The rim seal of claim 1, wherein the tank cover comprises sheet metal secured to the radial beams, the sheet 30 metal extending over and against a top surface of the thrust ring in a sealed connection.
